UNITED STATES PATENT OFFICE

EDWIN W. NORTH, OF ROCKFORD, ILLINOIS, ASSIGNOR TO NATIONAL LOCK CO., OF
ROCKFORD, ILLINOIS, A CORPORATION OF DELAWARE

DESIGN FOR AN ESCUTCHEON PLATE

Application filed August 14, 1931. Serial No. 40,852. Term of patent 7 years.

To all whom it may concern:

Be it known that I, EDWIN W. NORTH, a citizen of the United States, residing at Rockford, in the county of Winnebago and State of Illinois, have invented a new, original, and ornamental Design for an Escutcheon Plate, of which the following is a specification, reference being had to the accompanying drawings, forming part thereof.

In the drawings:

Fig. 1 is an end elevation of the escutcheon plate.

Fig. 2 is a front elevation of the same.

I claim:

The ornamental design for an escutcheon plate as shown. EDWIN W. NORTH.
